AUTOMATICALLY REGULATED ADHESIVE APPLYING APPARATUS

Harry F. Thorn, Trenton, N. J., assignor to George W. Swift, Jr., Inc., Bordentown, N. J., a corporation of New Jersey

Application August 10, 1956, Serial No. 603,375

2 Claims. (Cl. 118—7)

In the machinery used for the manufacture of single faced corrugated paper, and also in manufacturing corrugated paper board, it has long been conventional to provide a rotating adhesive applying roll past which a corrugated paper web is continuously fed in such manner that adhesive carried by the roll is applied successively to the peaks of the corrugations as they pass the roll, the adhesively coated peaks being then successively pressed into contact with a traveling web to which the corrugated web is to be bonded, and heat being applied to promote the rapid and effective setting of the adhesive.

Prior to the present invention insofar as I am aware, regulation of the amount of adhesive thus applied has required manual adjustments which were made by the operator; customarily a scraper roll has been provided in the adhesive applying mechanism, which the operator could adjust manually to regulate the thickness of the adhesive film carried by the applicator roll, and in some prior machines a variable speed transmission (e. g. the Reeves variable speed transmission) was provided in the mechanism which drove the applicator roll, which variable speed transmission the operator could adjust manually to regulate the speed of rotation of the applicator roll in relation to the speed of travel of the corrugated web.

In either event the regulation of the amount of adhesive applied was haphazard and uncertain, being at the whim of the operator, so that in some instances a defective product was obtained, and substantial amounts of adhesive wasted. In accordance with the present invention, the speed ratio adjusting member of such a variable speed transmission is power actuated by a regulating system responsive to the speed of travel of the corrugated web past the applicator roll, in such manner that when the corrugated web is traveling at relatively high speed, the surface speed of the applicator roll more nearly approaches the speed of travel of the corrugated web, and when the corrugated web is traveling at relatively slower speed, the surface speed of the applicator roll is relatively slower as compared to the speed of travel of the corrugated web. Preferably the regulating system is so arranged that the ratio between the surface speed of the applicator roll and the speed of travel of the corrugated web, at given speeds in the higher range of web speed of travel, can be adjusted without affecting said ratio in the lower range of web speed, and vice versa. For example, the regulating system preferably is so arranged that at maximum speed of travel of the corrugated web, e. g. 500' per min., the regulating system can be set to produce a surface speed of the applicator roll at different ratios within the range of about 85% to 100% of the speed of travel of the corrugated web; and can also be set so that at low speed of travel of the corrugated web, e. g. 100' per min., a surface speed of the applicator roll at different ratios within the range of about 70% to 85% of the corrugated web speed, may be obtained. If the scraper roll above re-

2

ferred to, be set at what would normally be regarded in the trade as providing an adhesive film of minimum thickness on the applicator roll, the regulating system may be set to produce a surface speed of the applicator roll which is about 80% of the speed of travel of the corrugated web, when the latter is traveling at a speed of 100' per min.; and may also be set to produce a surface speed of the applicator roll which is about 93% of the speed of travel of the corrugated web, when the latter is traveling at 500' per min.; the above mentioned ratios being independently adjustable as above referred to. The scraper roll being initially set, and the regulating system being initially set to provide selected speed ratios respectively at selected maximum and minimum speeds of corrugated web travel, thereupon without requiring further attention by the operator, the regulating system will automatically cause the applicator roll to apply progressively increasing amounts of adhesive to the peaks of the corrugations as the speed of travel of the corrugated web is reduced from maximum down toward minimum, and conversely as the speed of corrugated web travel increases from minimum toward maximum, the amount of adhesive applied will progressively decrease. In this way, it is found that throughout the normal operating range in speed of travel of the corrugated web, adhesive in amounts needed to insure a satisfactory bond at the peaks of the corrugations, may be obtained under different speeds of operation without relying upon manual adjustments by the operator, thereby assuring a more uniform product of better quality, along with reduced consumption of adhesive. Further objects and advantages of the invention will be in part obvious and in part specifically pointed out in the description hereinafter contained which, taken in conjunction with the accompanying drawings, discloses a preferred form of apparatus constructed to operate in accordance with the invention; the disclosure however should be regarded as merely illustrative of the invention in its broader aspects. In the drawings:

Fig. 1 is a side elevation, partly schematic and partly in section, showing the invention applied to single faced corrugated paper which is passing to a so-called double backer in which latter double faced corrugated paper board is produced;

Fig. 2 is a side elevation showing more in detail, certain features which may be applied to the variable speed transmission used in practicing the invention; and

Fig. 3 is a combined circuit and block diagram of apparatus for regulating the speed of the adhesive applying roll with respect to the speed of the corrugated web.

The invention is shown in Fig. 1 as applied to a web 1 of single faced corrugated paper which is traveling through the adhesive applying apparatus shown at the right of the figure, to the entrance end of a double-backer 2 wherein a facing sheet or liner 2 is applied to the adhesively coated peaks of the corrugations of the web 1, to produce double faced corrugated paperboard, the adhesive being set by heat applied in the double-backer in the usual manner. The internal construction of the adhesive applying apparatus and double-backer will not be described in full detail since appropriate forms thereof are known in the art, but the adhesive applying apparatus may be understood as involving appropriate guide rolls 3, 4, and 5 past which the sheet of single faced corrugated paper 1 continuously travels in such manner that the peaks of the corrugations are successively brought into contact with a film of adhesive carried by the periphery of the rotary adhesive applicator roll 6. As shown an adjustable scraper roll 7 and scraper blade 8 of known construction are used in conjunction with applicator roll 6. Adjustment of the spacing of roll

7 from roll 6, in known manner enables the thickness of the adhesive film carried by roll 6, to be regulated. The adhesive used may be of any appropriate type, such as the silicate and starch types customarily used in water solution.

The double-backer is shown as provided with the usual traveling belt 9 which passes partially around a power driven drum 10 carried by a shaft 11, and operating over a table 12 which may be understood as heated in the usual manner to drive off water from the adhesive carried by the peaks of the corrugations, the adhesive being set by the time the double faced corrugated paperboard is delivered from the double-backer. As shown the facing sheet 2 travels from an idler roll 13, and over a heated apron 14 into the entrance end of the double-backer, where the adhesively coated peaks of the corrugated web 1 are progressively and successively pressed by the belt 9 into contact with the adjacent surface of the facing sheet 2 as the latter enters the double-backer.

For the purpose of regulating the amount of adhesive deposited on the peaks of the corrugations, a variable speed transmission such as the Reeves variable speed transmission shown in outline in the lower left hand portion of Fig. 1, may be employed. Appropriate details of internal constructoin for such a transmission are known in the art.

In the form shown, the speed of travel of the corrugated web through the adhesive applying apparatus and through the double-backer, is determined by the speed of travel of the belt 9, which serves to draw the paper sheet through the adhesive applying apparatus. The power input shaft 15 of the variable speed transmission is shown as driven in fixed relationship to the speed of travel of the belt 9, by means of a sprocket 16 carried by the shaft 11 and driving a chain 17 which in turn drives the sprocket 18 carried by shaft 15.

The power output shaft 19 of the variable speed transmission is shown in Fig. 1 as carrying a sprocket 20 which drives a chain 21. The chain 21 drives a gear 22 which meshes with a gear 23, which latter rotates the adhesive applicator roll 6. The rate of rotation of the applicator roll 6, and therefore the surface speed of roll 6 and the film of adhesive carried thereby, as compared to the speed of travel of the web 1 passing through the adhesive applying apparatus, depends upon the speed ratio at which the variable speed transmission 14a is set, and this ratio may be altered by rotation of the adjusting spindle 24, which latter (and associated parts which will not be described in detail) may be understood as of construction and mode of operation known in the art. By turning the adjusting member 24 in one direction or the other, the surface speed of the applicator roll 6 as compared to the speed of travel of the corrugated web 1, and therefore the amount of adhesive deposited on the peaks of the corrugations, may be increased or decreased.

The variable speed transmission accordingly is equipped with an appropriate regulating system which is responsive to changes in the speed of travel of the corrugated web, and which controls the setting of the adjusting member 24 to regulate the amount of adhesive applied to the peaks of the corrugations under different operating speeds, in the manner already described. The disclosed system is of the electrical type but should be regarded as only typical. In the form shown, a reversible electric motor 25 is indicated in Fig. 2 as controlling the setting of the adjusting member 24, through chain 26 and appropriate sprockets, and by providing this motor with appropriate control circuits correlating its direction of rotation, and amount of rotation, with the rates of rotation of the shafts 15 and 19 under different operating speeds of travel of the corrugated web, the amount of adhesive applied will be regulated in the manner previously described. In Fig. 2, tachometer generators 27 and 28 of previously known construction and mode of operation are shown as driven by a chain 29 and appropriate sprockets, from the power

input shaft 15 of the variable speed transmission, and similar tachometer generators 30 and 31 are indicated as being driven through chain 32 and appropriate sprockets, from the power output shaft 19 of the variable speed transmission. Appropriate control circuits including these generators and the adjusting motor 25, are shown in Fig. 3.

In general, the circuits for automatically controlling the ratio of the speed of the output shaft 19 to the speed of input shaft 15, illustrated schematically in Fig. 3, combine the output voltage of the generator 31 driven by the output shaft 19 with a fixed bias voltage and compare this combined voltage with the output voltage of the generator 28 driven by the input shaft 15. The voltage difference, if any, between the combined voltages and the output voltage of the generator 28 is used to control relays which cause operation of the motor 25 and hence rotation of the spindle 24 which adjusts the speed of the output shaft 19 with respect to the input shaft 15 in a manner such that the ratio of the speeds is maintained at the desired value. Due to the presence of a fixed bias voltage, the ratio will be different in value when the web speed is low from the value of the ratio when the web speed is high without readjustment of the controls when the web speed is changed.

In Fig. 3, one terminal of an alternating current source 35 is connected by a lead 36 to a conventional voltage regulator 37 and is connected by a lead 38 to a centrifugal switch 39. The other terminal of the source 35 is connected by a lead 40 to a manually operable switch 41 and to an indicating lamp 42. When the switch 41 is in the "Off" position as shown in Fig. 3, both the automatic circuits and the manually operable circuits for rotating the spindle 24 are deenergized. When the switch 41 is moved to the position marked "Man." the rotation of the spindle 24 may be controlled manually and when the switch 41 is in the position marked "Auto." the rotation of the spindle 24 is controlled by the automatic circuits, hereinafter described, provided that the web speed is in excess of approximately 100 feet per minute.

As described above, the output shaft 19 is coupled by means of the chain 32 to conventional tachometer generators 30 and 31 and to the centrifugal switch 39. The generators 30 and 31 provide output voltages at their terminals 43 and 44 and 45 and 46 respectively, which are variable with and proportional to the speed of rotation of the shaft 19. Terminals 43 and 44 are connected to one pair of terminals 49 and 50 of a known type of ratio meter 47 whose pointer 48 assumes a position dependent upon the magnitudes of the voltages supplied to its two pairs of terminals 49-52. If the generator 31 is provided with a pair of output windings, the terminals 49 and 50 may be connected to the terminals 53 and 54 of the second winding, as indicated in dotted lines in Fig. 3, and the generator 30 and the connections thereto may be omitted.

The centrifugal switch 39 is of a type which may be set so that when web speed is below 100 feet per minute and hence the speed of rotation of the shaft 19 is correspondingly low, the switch 39 is open, and so that when the web speed is about 100 feet per minute or greater, the switch 39 is closed, completing a circuit between the lead 38 and the lead 55 which is connected to the lamp 42 and between the lead 38 and the lead 56 which is connected to common terminal 63 the adjusting motor 25. The switch 39 is provided to render the automatic controls inoperative when the web speed is below about 100 feet per minute. The lamp 42 will light when the web speed is about 100 feet per minute or greater and, hence, will indicate that the proper speed for automatic operation has been attained.

The input shaft 15 is coupled by means of the chain 29 to a pair of conventional tachometer generators 27 and 28, which may be identical with the tachometers 30 and 31. The terminals 51 and 52 of the ratio meter 47 may be connected to the terminals 57 and 58 of the

generator 27 as shown in Fig. 3, or if the generator 28 is provided with two output windings, the terminals 51 and 52 may be connected to the terminals 59 and 60 of the second winding, as indicated in dotted lines in Fig. 3, and in the latter case, the tachometer 27 and the connections thereto may be omitted. The generator 28 has a pair of output terminals 61 and 62 which are connected to the automatic control circuit hereinafter described.

The reversible motor 25 has its common terminal 63 connected to one side of the A. C. source 35 through the centrifugal switch 39, and its remaining terminals 64 and 65 are connected by means of leads 66 and 67 to the manually operable switches 68 and 69, to the "Slow" and "Fast" switches 70 and 71, and to the front contacts 72 and 73 of the relays 74 and 75. When the switch 41 is in the "Man." position, the motor 25 may be operated by the switches 68 and 69 to cause rotation of the spindle 24 and, hence, change the ratio of speeds of the input and output shafts 15 and 19, operation of the switch 68 reducing or lowering the speed of shaft 19 and operation of the switch 69 increasing or raising speed of the output shaft 19.

The switches 70 and 71 are associated with the control box 76 used to control the main drive motor 77 and are closed when one or the other of the "Slow" and "Fast" buttons 178 and 179 are momentarily pressed to reduce or increase respectively the speed of the main drive motor 77. The switches 70 and 71 cause operation of the spindle 24 at the same time that the speed of the drive motor 77 is changed so that the ratio of speeds of the shafts 15 and 19 will be at approximately the desired value when the speed of the drive motor 77 reaches the desired speed. The switches 70 and 71 are provided merely to reduce the delay in reaching the desired ratio when the speed of the drive motor 77 is changed and, hence, if desired, the switches 70 and 71 and the connections thereto may be omitted.

When the switch 41 is in the "Auto." position, the coil 78 of the relay 74 is energized, and the coil 79 of the relay 75 is de-energized, and energizing circuit for the motor 25 is completed from the terminal 65 to the lead 40 as follows: lead 67, contact 72, armature 80, leads 81 and 82, contact 83, armature 84, leads 85 and 86 and switch 41. Such energization of coil 78 when coil 79 is de-energized causes rotation of spindle 24 in a direction which increases the speed of the output shaft 19.

When the switch 41 is in the "Auto." position and the coil 79 is energized, an energizing circuit for the motor 25 is completed from the terminal 64 to the lead 40 as follows: lead 66, contact 73, armature 84, leads 85 and 86 and switch 41. Such energization of coil 79 causes operation of the motor 25 and rotation of the spindle 24 in a direction which lowers the speed of the output shaft 19.

Energization of the coils 78 and 79 is controlled by a relay 87 having a holding coil 88, an operating coil 89, a three position armature 90, and a pair of contacts 91 and 92. The relay 87 may, for example, be a relay of the type known as a "Sensitrol" and sold by the Weston Electrical Instrument Corporation, Newark, New Jersey. The armature 90 of the relay 87 assumes a position dependent upon the magnitude and polarity of the energy supplied to the operating coil 89. When the coil 89 is de-energized or is supplied with only a small amount of energy, the armature 90 assumes a position intermediate to contacts 91 and 92, and when the coil 89 is supplied with a larger amount of energy, the armature 90 engages either the contact 91 or 92, depending upon the polarity of such energy. The holding coil 88 is provided to prevent "chattering" of the armature 90, and when the coil 88 is energized, the armature 90 will be held against the contact 91 or 92 which it has engaged because of energization of the coil 89.

When the armature 90 is in engagement with the contact 91, the coil 79 is energized by means of the following circuit: leads 36 and 93, arm 94 of an interruptor 95, contact 96, lead 97, coil 79, lead 98, contact 91, armature 90, leads 100 and 86, switch 41 and lead 40.

When the armature 90 is in engagement with contact 92, the coil 78 is energized by means of the following circuit: leads 36 and 93, arm 94, contact 96, lead 101, coil 78, lead 102, contact 92, armature 90, leads 100 and 86, switch 41 and lead 40.

Interruptor 95 is a well known device employed to reduce "hunting" or "over-control" by the motor 25. The interruptor 95 comprises in addition to the arm 94 and contact 96, heretofore mentioned, a contact 103, a serrated wheel 104 and a driving motor 105. When the motor 105 is energized, it rotates the wheel 104 causing the arm 94 which engages the wheel 104 to alternate between the contacts 96 and 103. The motor 105 is energized when either of the coils 78 and 79 is energized, the circuits being as follows: for energization of coil 79, leads 36 and 106, contact 107, armature 108, lead 109, contact 110, armature 111, lead 112, motor 105, leads 113 and 86, switch 41 and lead 40; for energization of coil 78, leads 36 and 114, contact 115, armature 111, lead 112, motor 105, leads 113 and 86, switch 41 and lead 40.

The coils 78 and 79 normally are de-energized, and their associated armatures are in the positions shown in Fig. 3. Therefore, the motor 105 normally is de-energized and the arm 94 is against the contact 96 permitting energization of the coils 78 or 79 by the relay 87. However, when either coil 78 or 79 is energized, the corresponding armature 111 or 108 engages its associated contact 115 or 107, causing energization of motor 105.

Wheel 104 turns, causing its arm 94 to engage its contact 103, which completes an energizing circuit for the holding coil 88 as follows: leads 36 and 93, arm 94, contact 103, leads 116 and 117, coil 88, leads 100 and 86, switch 41 and lead 40. Since movement of the wheel 104 disengages the arm 94 from the contact 96, the coil 78 or 79 which has been energized previously, becomes de-energized, interrupting the above described circuit for energization of motor 105, but because of the position of the arm 94, a new energizing circuit for the motor 105 is completed as follows: leads 36 and 93, arm 94, contact 103, lead 116, contact 118, armature 108, lead 109, contact 110, armature 111, lead 112, motor 105, leads 113 and 86, switch 41 and lead 40. Because of this new energizing circuit, the motor 105 continues its rotation until the arm 94 again engages the contact 96.

Although engagement of the arm 94 with the contact 96 interrupts the last-mentioned circuit, the arm 94 may be caused to engage contact 96, either due to inertia of the interruptor or because the arm 94 engages the contact 96 before the arm 94 becomes disengaged from the contact 103.

It will be apparent from the foregoing that when either of the coils 78 and 79 is energized by operation of the relay 87, the motor 25 will be energized and will operate the spindle 24 for a short period of time, determined by the speed of operation of the interruptor 95. The motor 25 will then become de-energized after the interruptor 95 has rotated its wheel 104 a small amount and will remain de-energized until the arm 94 again engages the contact 96. If at the time that the arm 94 re-engages the contact 96, the armature 90 has become disengaged from its associated contacts 91 and 92, the motor 25 will not be re-energized. However, if the armature 90 remains in contact with one of the contacts 91 and 92, or engages a different one of the contacts 91 and 92, the motor 25 will be re-energized when the arm 94 engages the contact 96, and the cycle above described will be repeated.

Energization of the coil 89 of the relay 87 is controlled by a circuit which combines the output voltages of the generators 28 and 31 and a biasing circuit connected to

the voltage regulator 37. The regulator 37 is energized over an obvious circuit when the switch 41 is in the "Auto." position.

The output of the voltage regulator 37 is connected to any well known type rectifier 119 and may, for example, be a bridge rectifier employing selenium or copper oxide diodes. The output of the rectifier 119 in the polarity indicated in Fig. 3 is connected to a voltage divider 120, an intermediate point 121 of which is connected by a lead 122 to one end of a potentiometer 123. One end of the divider 120 is connected to one end of potentiometer 124 by a lead 125. The ends of the potentiometer 124 are connected by leads 126 and 127 to the terminals 61 and 62 of the generator 28. The adjustable arm 128 of the potentiometer 124 is connected to one end of a potentiometer 129, the latter potentiometer 129 being used to control the sensitivity of the apparatus and, hence, the response of the relay 87. The operating coil 89 of the relay 87 is connected by leads 130 and 131 to the adjustable arm 132 and to one end of the potentiometer 129, adjustment of the arm 132 varying the amount of energy supplied to the operating coil 89.

The potentiometer 123 is connected in series with a potentiometer 133 whose adjustable arm 134 is connected to one end of the potentiometer 129. The end of the potentiometer 133 remote from its junction point with the potentiometer 123 is connected by a lead 135 to terminal 45 of the generator 31 and adjustable arm 136 of the potentiometer 123 is connected by a lead 137 to the terminal 46 of the tachometer 31.

It will be apparent from an examination of the connections of the potentiometers 123 and 133 that these two potentiometers combine the bias voltage supplied by the divider 120 with the voltage supplied by the generator 31. Also, the potentiometer 129 has developed thereacross a voltage whose magnitude and polarity depends upon the difference between the combined bias voltage and output voltage of generator 31 on the one hand and the output voltage of the generator 28 on the other hand. The arm 136 affects, primarily, the magnitude of the bias voltage added to the output voltage of the generator 31 and the setting of arm 134 determines, primarily, the amount of voltage applied to one end of potentiometer 129. The setting of arm 128 determines the magnitude of the voltage applied to the opposite end of potentiometer 129, the voltage being derived from generator 28. Setting of the arm 128 is determined by the sensitivity of the relay 87 and other operating conditions and is a factory fixed setting. It has been found that the setting of the arm 136 may be used to control the ratio of the adhesive applicator roll speed to the web speed when the latter speed is relatively low, e. g., 100 feet per minute. Also, it has been found that the setting of the arm 134 may be used to control this ratio when the web speed is relatively high, e. g., 500 per minute. Although there is some interaction between the settings of the arms 134 and 136, they are sufficiently independent in effect to permit control of the ratio at high web speed and low web speed respectively.

The procedure for setting up the various controls is as follows:

(1) With the switch 41 in the "Off" position, arm 134 is moved until it is about three-quarters of the distance between the junction point of potentiometer 133 with potentiometer 123 and the end remote from the junction point, the arm 134 being nearer the latter end.

(2) The arm 136 is moved to the end of the potentiometer 123 connected to the potentiometer 133.

(3) The arm 132 is set about midway between the ends of potentiometer 129.

(4) The main drive motor 77 is adjusted until the web speed is slightly higher than 100 feet per minute, and the switch 41 is moved to the "Auto." position.

(5) The arm 136 is adjusted slowly until the ratio meter 47 indicates the desired ratio with low web speeds.

(6) The speed of the main drive motor 77 is adjusted to its "normal high" production speed, e. g. 500 feet per minute, and the arm 134 is adjusted slowly until the ratio meter 47 indicates the ratio desired at high web speeds.

(7) Steps 4, 5 and 6 are repeated to provide more accurate settings. For intermediate speeds, the ratio will be intermediate, the low speed and high speed values, although the ratio will not be directly proportional to speed, the apparatus described providing a non-linear relationship between ratio and web speed.

(8) If desired, the sensitivity arm 132 may be adjusted to obtain higher sensitivity. However, the sensitivity should be increased only until "hunting" occurs and then the sensitivity should be reduced.

It will be apparent from the above that if it is desired to change the low speed and high speed ratios to which the controls are set, the steps set forth above should be repeated for the new ratios.

The following example will illustrate the operation of the control circuit. Let it be assumed that the voltages applied to the ends of potentiometer 129 must be substantially equal in magnitude and opposite in polarity for equilibrium, and let it also be assumed that the generators 28 and 31 provide equal output voltages for the same speed of rotation. Suppose that at the time the web speed is 100 feet per minute, approximately 5 volts are applied to the end of potentiometer 129 connected to the arm 128 by the generator 28. When the speed of the shaft 19 is 80% of the speed of shaft 15, and the arm 134 is properly adjusted as set forth above, the generator 31 will apply 4 volts to the opposite end of the potentiometer 129. Accordingly, to obtain balance conditions or equilibrium, the arm 136 must be set to supply approximately one volt from the bias source.

When the web speed is increased, the generator 28 will supply a higher output voltage, and let it be assumed that the new voltage is approximately 10 volts. Under these conditions, the generator 31 will be required to supply 9 volts to the opposite end of potentiometer 129 because the voltage supplied from the bias source is fixed and does not vary with speed. Accordingly, the output shaft 19 must, under the high speed conditions, be rotating at a speed which is approximately 90% of the speed of the shaft 15. Thus, without any readjustment of the arms 128, 132, 134 and 136, the ratio of the speed of the output shaft 19 to the speed of the input shaft 15 will change between predetermined limits, when the speed of the drive motor 77 is varied.

In summary, except for details of operation heretofore described, the operation of the automatic ratio controlling circuits is as follows:

(1) When the portion of the output voltage of the generator 31 combined with the bias voltage applied to one end of the potentiometer 129 is substantially equal to the portion of the output voltage of the generator 28 applied to the potentiometer 129, the armature 90 remains in its intermediate position and the motor 25 is at rest.

(2) When the portion of the output voltage of the generator 28 applied to the potentiometer 129 is greater than the portion of the combined voltages applied to the potentiometer 129, the armature 90 engages the contact 92, energizing the coil 78 and causing operation of the motor 25 and hence, rotation of the spindle 24, in a direction which increases the speed of rotation of the output shaft 19.

(3) When the portion of the combined voltages applied to the potentiometer 129 is greater than the portion of the output voltage of the generator 28 applied to potentiometer 129, armature 90 engages contact 91, energizing the coil 79 and causing operation of the motor 25

and hence, rotation of the spindle 24, in a direction which reduces the speed of the output shaft 19.

Accordingly, the ratio of the speed of the output shaft 19 to the speed of the input shaft 15 will be maintained automatically at a value determined by the settings of the arms 128, 134 and 136.

While the invention has been disclosed as applied to a paper board making machine of the above described specific form, and using a regulating system as specifically described above, it should be understood that changes may be made therein without departing from the invention in its broader aspects, within the scope of the appended claims.

What is claimed is:

1. Adhesive applying apparatus of the character described for the bonding of the peaks of a corrugated web to a facing web, including an adhesive applicator roll, power driven means for progressively moving a web past said applicator roll, a variable speed transmission having its power input member driven in definite speed relation to said power driven means and its power output member connected in driving relation to said applicator roll, and means responsive to variations in speed of said power driven means, for adjusting said variable speed transmission to decrease the relative surface speed of said applicator roll as compared to the speed of travel of said web, upon decrease in speed of said power driven means, and increase the relative surface speed of said applicator

roll as compared to the speed of travel of said web, upon increase in speed of said power driven means.

2. Adhesive applying apparatus of the character described for the bonding of the peaks of a corrugated web to a facing web, including an adhesive applicator roll, power driven means for progressively moving a web past said applicator roll, a variable speed transmission having its power input member driven in definite speed relation to said power driven means and its power output member connected in driving relation to said applicator roll, and means responsive to variations in speed of said power driven means, for adjusting said variable speed transmission to decrease the relative surface speed of said applicator roll as compared to the speed of travel of said web, upon decrease in speed of said power driven means, and increase the relative surface speed of said applicator roll as compared to the speed of travel of said web, upon increase in speed of said power driven means, said means responsive to variations in speed of said power driven means, having devices affording adjustment of the ratio of applicator roll surface speed to web speed at a given speed in the high speed range of web speed, and also at a given speed in the low speed range of web speed.
